(57) CLAIM

The ornamental design for a pair of beard straps for face mask, as shown and described.

DESCRIPTION

FIG. 1 is a front perspective view of a pair of beard straps for face mask, showing my new design;

FIG. 2 is a front elevation view thereof;

FIG. 3 is a rear elevation view thereof;

FIG. 4 is a left side elevation view thereof, the right side elevation view being a mirror image thereof; and,

FIG. 5 is a top plan view thereof, the bottom plan view being a mirror image thereof.

The broken lines in the drawings depict environmental subject matter that forms no part of the claimed design.

1 Claim, 3 Drawing Sheets
